(57) **CLAIM**

The ornamental design for a finger guard for use over door hinge, as shown.

DESCRIPTION

FIG. 1 is a front perspective view of a finger guard for use over door hinge showing our new design;

FIG. 2 is a left side elevation view thereof, the right side being a mirror image thereof;

FIG. 3 is a rear elevational view thereof;

FIG. 4 is a front elevational view thereof;

FIG. 5 is a top plan view thereof; and,

FIG. 6 is a bottom plan view thereof.

The texturing shown in dashed lines (specifically the pattern formed by paired elliptically-shaped line segments) forms no part of the design herein.
